SUSPENSION MEANS FOR SWING SIGNS

Frederick A. Lippold, Chicago, Ill., assignor to Reliance Advertising Co., Chicago, Ill., a corporation of Delaware

Application July 31, 1935, Serial No. 33,998

1 Claim. (Cl. 40—128)

This invention relates to advertising signs which are hung from a horizontal support and are free to respond to wind pressure by swinging around a horizontal axis. 5 The objects of the invention are to improve the hanger means in the matter of strength and to include therewith a resilient resistance to swinging and a positive stop to limit the angular motion of the sign and prevent contact thereof with illumination devices which extend outwardly from the sides of the horizontal supporting arms. 10

The objects of the invention are accomplished by means of constructions as illustrated in the drawings, wherein

Fig. 1 is a fragmentary face view of a sign and its supporting structure.

Fig. 2 is an enlarged transverse sectional detail showing one of the hangers and a sign suspended therefrom.

Fig. 3 is a front view of the construction shown in section by Fig. 2.

Fig. 4 is a perspective view of stop and swivel bearing plates which are part of the hanger.

Fig. 5 shows in perspective additional swivel bearing plates for receiving a bolt from which the sign is suspended.

Fig. 6 is a perspective view of one of the hanger clamps.

Fig. 7 is a fragmentary side view of a modified form of the hanger.

Fig. 8 is a sectional view as indicated by the line 8—8 on Fig. 7.

Fig. 9 is a detail of an improved eye-bolt and cooperative bearing plate which is employed in the construction illustrated by Figs. 7 and 8.

A construction of the class to which this invention relates consists generally of a vertical pole having a laterally extending arm from which the sign is suspended. The customary suspension means for the sign consists of eye-bolts passing through the arm with links connecting the eye bolts to the sign frame.

There are objections to such an arrangement which become particularly evident in high winds, sometimes of sufficient strength to cause the signs to swing against lighting equipment, resulting in breakage. The new arrangements of suspension means provide more durable constructions and also resiliently restrain swinging motions of the signs and prevent contact thereof with the lighting means.

The construction illustrated by Sheet 1 of the drawings includes the old arrangement of vertical pole 1, carrying the horizontal arm 2 from which

the sign frame 3 is suspended. The pole 1 and arm 2 serve as conduits for electrical conductors leading to lateral extensions 4 from arm 2 which extensions carry sign lighting equipment, including reflectors 5.

The new construction relates to the hangers which are detailed in the drawings. The hangers include a pair of clamp plates 6, one of which is shown by Fig. 6, and which embrace the arm 2 and are clamped thereto by means of bolts 7 which serve to draw the clamp elements together. Each clamp member has welded thereto at one end one of the suspension plates 8 and 9, and at the opposite edge one of the suspension and stop plates 10 and 11. These plates are welded either at the edge or on the curved surface of one of the clamp members to form a substantially integral part thereof. To further strengthen the structure the plate 10 is riveted to the plate 11 by rivet 12, and the plate 8 is riveted to the plate 9 by rivet 13. Thus when the clamps are applied to the horizontal arms 2 the perforations 14 in the plates 8, 9, 10 and 11 come into alignment for receiving bolt 15 passing through a bearing in the upper end of sign frame 16.

Surrounding the bolt between the pairs of hanger plates is a bushing 17, and placed over the bushing is a coil spring 18 having its ends respectively inserted in a perforation 19 of the sign frame, and in a perforation 20 in plate 8.

The plates 10 and 11 have inclined stop shoulders 21 and 22 for cooperating with the inclined shoulders 23 and 24 on the sign frame.

According to the above detailed description each sign hanger consists in the clamp members 6 which embrace the horizontal support 2 and have welded thereon the depending members 8, 9, 10 and 11, which form the bearing for bolt 15 from which the sign is suspended and is free to swing thereon as resisted by spring 18.

In the operation of this form of construction if the sign swings under wind pressure it encounters the progressively increasing resistance of spring 18 as the sign moves away from its normal vertical position. The extreme limit of movement of the sign is as indicated by the broken lines in Fig. 2, when one of the shoulders 23 or 24 thereof engages the inclined stop 21 or 22 on one of the members 10 or 11.

The form of construction shown in Figs. 7, 8, 50 and 9 operates the same as that illustrated by Sheet 1 of the drawings, spring 25 in this form being the equivalent of spring 18, Fig. 3.

One end of spring 25 is passed through the aperture 26 in the head of eye-bolt 27. The 55

opposite end of the spring is inserted in an aperture 28 in a bracket member 29 secured to the sign frame 30 by rivets 31.

The head of the eye-bolt is formed with stop shoulders 32 which serve to limit the swinging motion of the sign when shoulders 33 on the latter engage the shoulders 32. The shoulders 33 are formed on plates 34 which are welded to the vertical portion 35 of the sign frame and to the bracket 29.

The curved surfaces 36 on the head of the eye-bolt are welded to the tubular arm 37 forming the horizontal support from which the sign is suspended.

The arcuate surface 38 on the head of the eye-bolt serves as an additional bearing for the sign as it is engaged by the concave surface 39 of plate 34.

The sign swings on bolt 40 which passes through an aperture 41 in an ear 42 at the upper end of frame element 35. The bolt also passes through a similar aperture 43 in the upper end of bracket 29 and through the aperture 44 in the eye-bolt. Spring 25 is spaced from the shank of bolt 40 by a bushing 45. The arm 37 is drilled out at 46 to receive the eye-bolt which is clamped in place by the nut 47.

This type of construction is intended to take the place of old arrangements of eye-bolt and link suspension means for signs and the new form of eye-bolt 27 is intended to fit the same apertures 46. This form of eye-bolt which has its head welded to the horizontal support 37 has the advantage of reinforcing the bolts against shear. The operation of the modified form of the construction is as indicated in Fig. 8 which shows by dotted lines the extreme motion of the sign around the axis of bolt 40 as limited by shoulder 33 on the sign frame engaging shoulder 32.

I claim:

In a construction of the class described, a horizontal support, a sign frame, a suspending means for the sign frame, said suspending means comprising a rigid attachment to the support and including a bearing for the sign frame and stops for limiting motion of the sign frame around said bearing, said sign frame having shoulders for engagement with said stop elements, a pivot passing through said sign frame and suspension means, and a coil spring surrounding said pivot and having its ends respectively in engagement with the suspension means and the sign frame.

FREDERICK A. LIPPOLD.
